UNITED STATES PATENT OFFICE.

FRANCIS J. DOYLE, OF CHICAGO, ILLINOIS.

FURNACE.

1,108,976.

Specification of Letters Patent.

Patented Sept. 1, 1914.

Application filed October 5, 1909, Serial No. 521,103. Renewed January 27, 1913. Serial No. 744,590.

To all whom it may concern:

Be it known that I, FRANCIS J. DOYLE, a citizen of the United States, residing at Chicago, in the county of Cook and State of Illinois, have invented certain new and useful Improvements in Furnaces, of which the following is a specification.

This invention relates to improvements in furnaces, and refers more specifically to a furnace provided with a regenerative combustion chamber as an auxiliary to the primary combustion chamber of the furnace.

Among the salient objects of the present invention are, to provide a construction whereby the smoke and coal gases are more perfectly consumed and a higher heating efficiency secured; to provide a construction in which the usual fire box or primary combustion chamber of the furnace is utilized chiefly as a gas distilling device while the principal combustion occurs in the auxiliary combustion chamber which is located outside of the main body of the furnace but within the sheet metal casing thereof and is therefore capable of more effectively radiating the heat generated therein than would be the case were the regenerative device arranged within the main body of the furnace; to provide a construction in which the gases of combustion are caused to circulate through a system of return flues arranged in such manner as to effect a more perfect and intense combustion; to provide a simple and effective means for supplying heated air to the regenerative device; to provide means whereby the whole or only a portion of the heating capacity may be put in use, throwing out of operation a portion of the regenerative device; to provide a construction which conforms in general appearance to the conventional types of furnaces now in use; and in general to provide a simple and improved construction of the character referred to.

To the above ends the invention consists in the matters hereinafter described and more particularly pointed out in the appended claims.

The invention will be readily understood from the following description, reference being had to the accompanying drawings, in which—

Figure 1 is a front elevation of a furnace embodying the present invention; Fig. 2 is

a vertical sectional view through Fig. 1; Fig. 3 is a top plan view of the furnace shown in Fig. 1 with the upper part of the sheet metal casing removed and also the dome of the furnace proper; Fig. 4 is a vertical sectional view of a modification; Fig. 5 is a top plan view of the furnace shown in Fig. 4 with the upper part of the outer casing removed.

Referring to the drawings, (Figs. 2 and 3) 1 designates a sheet metal outer casing provided with outleading hot air conducting pipes 2—2, leading to the apartments to be heated, and also with a feed door 3 through which fuel is fed to the furnace, and an ash door 4 opening into the ash pit thereof, there being the usual connection between said doors and the fire box and ash pit respectively.

The furnace proper is located within this casing and comprises a conical base shell 5 with double walls to provide an air space 6 therebetween which communicates with the atmosphere within said outer casing through openings 7. Mounted upon said base is a fire bowl 8 also having double walls to provide a corresponding air space 9 therebetween, said space being closed at its upper edge by the members 9', and communicating at its lower edge with the air space 6. 10 designates a grate mounted upon a suitable support at the juncture of said base 5 and bowl 8. Mounted upon the upper edge of the inner wall of said bowl 8 is a cylindrical member 11, provided on its upper edge with a dome 12 and forming the primary combustion or distilling chamber of said furnace, while 13 designates a series of partition members mounted upon the inner wall of said cylindric member and forming passageways 14 into which a portion of the smoke and gases from the fuel pass, while the other portion of said smoke and gases rises in the primary combustion chamber and is directed downwardly by the dome 12 into the upper end of the passageways 14, from which they escape through outleading pipes 15 communicating therewith, said outleading pipes 15 being provided on their under sides with openings 16 communicating with the air space 9, whereby air passing through said space against the inner wall of said fire bowl is heated and conducted into said pipes 15 where it is mixed with the smoke and gases

from the primary combustion chamber as they pass into an auxiliary combustion chamber or regenerating device, designated as a whole 17, within which the principal combustion of said gases takes place.

The regenerative device 17 comprises an outer casing having the general form of a horse shoe and of rectangular form in cross section. 18 designates a downwardly concaved partition casting mounted within said outer casing a short distance from the bottom thereof and provided with a series of conical flue members 19, upon the upper ends of which rests a plate casting 20 extending throughout the length of said outer casing and provided with openings 21 which register with said flue members, and also provided throughout its length, in the middle thereof, with a series of openings 22 which afford communication between the space around said flue members 19 and the space above said plate casting 20. Upon the upper outer edges of said plate casting 20 is a co-extending partition member 23 which terminates at its upper edge short of the top wall of said outer casing 17, while 24—24 designate a pair of correspondingly extending partition members mounted upon said plate casting 20 and extending to the top of the outer casing 17, in the manner shown, said latter partition members forming a closed chamber 25 between which and the space around said flue members 19, the openings 22 afford communication. 26 designates an eduction pipe at the rear of the furnace which leads from said chamber 25 and through which the products of combustion are finally carried to the smoke chimney.

It will be understood from the above that as the gases of combustion from the primary combustion chamber pass into the space 14 and out through the connecting pipes 15, supplies of heated air are mixed therewith from the air passage 9 and the whole passes into the auxiliary combustion chamber or regenerative device 17, passing upwardly through the flue members 19, thence downwardly against the outer wall of the device 17, thence inwardly between the flue members 19 and upwardly into the chamber 25, from which they are carried off by the eduction pipe 26. The course of this circuitous passage is clearly indicated by the arrows and also the course of the atmospheric air up through the base and fire bowl. During the passage of said gases of combustion through said auxiliary combustion chamber, supplied with heated air, a more complete and intense combustion is obtained, resulting in a great saving of fuel.

Describing the embodiment shown in Figs. 4 and 5, the outer sheet metal casing, the conical base, primary combustion chamber and air passages are the same in construc-

tion and arrangement as is shown in Figs. 2 and 3, but instead of a single auxiliary combustion chamber or regenerative device, three such devices 27, 28 and 29 are provided, which have communication with the primary combustion chamber through out-leading pipes 30, 31 and 32, respectively, which may be provided with dampers, as shown at 33—34, for controlling the passage from said primary combustion chamber, thereby making it possible to use one, two 75 or all three of said separate devices as may be desired. 35 designates a pipe connecting the discharge of each device and communicating with a final eduction pipe 36 leading to the smoke chimney. 80

The regenerative devices or auxiliary combustion chambers 27, 28 and 29 are alike, each comprising a cylindrical outer casing communicating at its lower side with the primary combustion chamber of the furnace through one of the out-leading pipes 30, 31 or 32, and each provided therein near the bottom thereof with a downwardly convexed partition casting 37 having the upstanding conical flue members 38. Upon said flue members is mounted a plate casting 39 provided with openings 37 therethrough which register with said flue members and also provided with a central opening 38' to the space 39' between said conical flue members. 40 designates a cylindrical partition member mounted upon said plate casting and terminating short of the top wall of said outer casing. Mounted concentrically within said partition member 40 is a second and smaller cylindrical partition member 41 which communicates at its lower end with the central opening through said plate casting and at its upper end with the connecting pipe 35. It will thus be seen that the gases of combustion pass into the out-leading pipes 30, 31 and 32, thence upwardly in the regenerative device through the conical flue members 38 and into the cylindrical member 40, thence downwardly on the outside of said cylindrical member against the outer wall of the device, thence inwardly between the flue members 38 and upwardly through the central opening 38' in the plate casting into the member 41 and finally into the connecting 115 pipe 35 from which they are conveyed to the eduction pipe 36, the circulating course being substantially the same as that in the construction shown in Figs. 2 and 3.

In both embodiments of the above described invention, the primary object has been to produce a furnace in which a more complete and intense combustion is secured. This has been accomplished by utilizing the primary combustion chamber as a distilling or generating chamber from which the gases of combustion pass into an auxiliary combustion chamber, being supplied with heat-

ed atmospheric air as they enter said latter chamber. The circuitous passage through said auxiliary combustion chamber, increasing in temperature as it advances, results in causing an intense combustion of the gases which are usually passed off through the smoke chimney.

While I have herein shown and described what I consider the preferred form of the invention, it is obvious that many alterations and modifications in the details of construction and arrangement can be made without departing from the spirit of the invention, and I do not therefore, limit the invention to the details shown and described, except in so far as such details are made the subject matter of specific claims.

I claim:

1. A furnace comprising in combination, an outer casing, a base member, a fire bowl mounted upon said base member, said base member and fire bowl being provided with a surrounding air passage communicating at one end with the outer atmosphere, a cylindric member mounted upon said fire bowl and constituting the primary combustion chamber of the furnace, an auxiliary combustion chamber within said outer casing and having a circuitous passage there- 25 through and connecting members forming passageways from said primary combustion chamber to said auxiliary combustion chamber through which the gases of combustion pass, said connecting members having communication with said air passage, whereby the gases of combustion are supplied with heated atmospheric air as they pass from said primary combustion chamber into said auxiliary combustion chamber, for the purpose described.

2. In a furnace, the combination with the outer casing, fire bowl and combustion chamber thereof, of one or more auxiliary combustion chambers within said outer casing and arranged exteriorly of said primary combustion chamber, connecting pipes between said primary combustion chamber and said auxiliary combustion chamber through which the gases of combustion from said primary combustion chamber pass into said auxiliary combustion chambers, there being air passageways adjacent said fire bowl and communicating at one end with the outer atmosphere and at its other end with said connecting pipes whereby heated atmospheric air is mixed with said gases of combustion as they pass from said primary combustion chamber into said auxiliary combustion chamber, said auxiliary combustion chamber being provided with partition members forming a circuitous passage therethrough wherein a more complete and intense combustion of said gases takes place, and dampers in said connecting pipes for

regulating and controlling the communication between said primary and auxiliary combustion chambers, substantially as described.

3. A furnace comprising in combination a conical base member with double walls, a fire bowl with double walls mounted upon said base member, whereby an air passage is provided between the walls of said base member and fire bowl with an opening to the outer atmosphere, a cylindrical member mounted upon said fire bowl and forming the primary combustion chamber thereof, outleading pipes from said primary combustion chamber which also have communication with said air passage, and a regenerative device communicating with said outleading pipes into which the products of combustion pass mixed with heated atmospheric air from said air passage, said regenerative device comprising a closed chamber provided with partition members forming a circuitous passage within which a more complete and intense combustion takes place, and an eduction pipe leading from said regenerative device, substantially as described.

4. In a furnace, the combination with the fire bowl and combustion chamber thereof, of an outer wall about said fire bowl forming an air space therebetween which has communication with the outer atmosphere, one or more auxiliary combustion chambers mounted upon said furnace and having communication with the primary combustion chamber thereof and with said air space, whereby the gases of combustion from said primary combustion chamber are supplied with heated atmospheric air as they pass into said auxiliary combustion chambers, dampers for controlling the admission of said gases of combustion to said auxiliary combustion chambers, said auxiliary combustion chambers being provided with partition members forming a circuitous passage therethrough and a connecting pipe into which said auxiliary combustion chamber passages merge, said connecting pipe discharging into the smoke chimney, substantially as and for the purpose described.

5. In a furnace, the combination with the fire bowl and combustion chamber thereof, and a grate in the fire bowl, of a plurality of flues within the combustion chamber communicating at their upper and lower ends with the combustion chamber to receive gases and products of combustion from the burning fuel, an outlet from each flue to the exterior for the products of combustion and gases, means for supplying air to the products of combustion and gases as they enter the outlets, a common auxiliary combustion chamber encircling in greater part the combustion chamber and connected with each of said outlets, said auxiliary combustion

chamber being constructed to afford a circuitous path for the hot products of combustion, gas and air to cause a more thorough mixture and combustion, an outlet from said auxiliary combustion chamber, an outer

chamber, and means for distributing the heated air from said casing.

FRANCIS J. DOYLE.
